TONE MODULATORS OPERATING AT VARYING RATES OF SPEED

Filed March 18, 1927

Fig. 1

Fig

A technical drawing showing a mechanical assembly. A horizontal bar is supported by a vertical post. A horizontal rod is attached to the post and extends to the right. The distance from the vertical post to the center of the horizontal rod is labeled 2.30. The distance from the vertical post to the left end of the horizontal rod is labeled 2.29. The distance from the vertical post to the right end of the horizontal rod is labeled 2.28. The distance from the vertical post to the right end of the horizontal bar is labeled 2.25.

UNITED STATES PATENT OFFICE.

JOHN HAYS HAMMOND, JR., OF GLOUCESTER, MASSACHUSETTS.

TONE MODULATORS OPERATING AT VARYING RATES OF SPEED.

Application filed March 18, 1927. Serial No. 176,386.

This invention relates to improvements in music modulators and more particularly to the control of tone shading and musical dynamics.

- 5 The present invention has particular reference to a system of tone shading for musical instruments of the percussive type, and provides improved control of musical dynamics in the different parts of the musical 10 scale. It may be employed, however, with equal advantage in connection with any other type of musical instrument where it may be desired to control the tone shadings of the musical scale.
- 15 The principal object of the invention is to provide means for modulating and reflecting the sound produced by a musical instrument differently in different parts of the scale.
- 20 A feature of the invention relates to the provision of a plurality of modulating reflectors operable at different rates. Another feature relates to the provision of improved means for actuating modulating reflectors at 25 different rates.

Other objects will appear from the following description taken in connection with the accompanying drawings in which—

Figure 1 is a plan view and Figure 2 is 30 a front elevation partly in section of a musical instrument of the percussive type.

Figure 3 is a section taken on the line 3—3 of Figure 1.

Like reference characters refer to like 35 parts in the several figures of the drawings.

In the following description and claims, parts, characteristic features and functions will be identified by specific names for convenience of expression, but they are intended 40 to be as generic in their application as the art will permit.

Referring to Figures 1, 2 and 3 of the drawings, there is shown for the purpose of illustrating one form of the invention, a 45 grand piano comprising a casing 10 supported on suitable feet in a conventional manner and having positioned therein a plurality of strings such as 11, 12, and 13, tuned to the notes of the musical chromatic scale. The strings 11 of the left-hand portion of Figure 2 are assumed to be tuned to the lower notes of the scale and the strings 13 in the right-hand end to the upper notes of the scale, and the intermediate strings such 55 as 12 tuned to the intermediate notes of the scale. The strings 11, 12 and 13 are

stretched upon a conventional frame 14 and are preferably arranged in a single plane, in the case illustrated, a horizontal plane. A sounding board 60 is provided within the 60 casing 10, in a plane parallel to the plane of the strings.

For each note of the musical scale there is provided a hammer such as 15, arranged to set into vibration by percussion the 65 strings tuned to the respective note. The strings tuned to notes of low pitch are of greater mass than the strings of high pitch, and accordingly the energy produced by the low pitched string is of greater intensity 70 than that produced by the high pitched strings. The strings tuned to each note of the scale are actuated by means of a piano action 16 and a key 17 in a conventional 75 manner. The keys such as 17 are arranged in a manual 18 and may be operated manually in a conventional manner to produce musical sound.

The casing 10 is provided on its inner face 80 with a layer 50 of sound reflecting material such as a smooth metal sheet. The casing is provided with oppositely disposed controllable apertures in planes above and below the plane of the strings. For controlling the extent of opening of these apertures so as to reduce or otherwise control the volume of sound emitted from the instrument there is provided a plurality of groups of sound wave reflectors. Each reflector is preferably in the form of an elongated flat member 20 having bevelled lateral edges and pivotally mounted to rotate about its longitudinal axis (see Figure 2), and having a facing 51 of metal on its inner surface. Each reflector is provided with an 90 arm 21 rigidly fastened thereto and the arms of the upper groups of reflectors are pivotally interconnected by connecting rods 22. The arms of the lower group are connected to a connecting rod 23. One of the arms in the upper group is operatively connected by means of a link 24 to a radial arm on a rotatable shaft 25 extending through the casing 11 and mounted in spaced bearings 26, 26 secured to the casing. A collar 27 is mounted on the shaft 25 for maintaining the shaft in fixed longitudinal relation with respect to the bearings 26. The lower connecting rod 23 is operatively connected to the shaft 25 by means of a link 28 extending from the connecting rod 23 to a second radial arm 29 affixed to the shaft 25.

For rotating the shaft 25 at will, there is provided an operating mechanism including an arm 30 secured to the shaft and pivotally connected with one end of a link 31 the other end of which is secured to one arm of a bell crank lever 32. The bell crank lever 32 is pivotally mounted as at 33 on a bracket 34 depending from the piano casing 11. The other arm of the bell crank lever 10 32 is engaged by a vertically reciprocating rod 35 communicating with one pedal 36 of a group of pedals mounted in a pedal block 37, the other pedals 38 and 39 of which are connected to any desired portions of the 15 piano such as the sostenuto and loud pedal action as may be desired. A leaf spring 40 is secured to the casing of the piano and engages the bell crank lever 32 for normally maintaining the bell crank lever and the associated parts in the position shown in 20 Figure 2.

Each of the arms 21 of the upper group is of a different length, and extends at a different angle with respect to the plane of the 25 respective closure. A predetermined movement of the upper rod 22 thus imparts a different degree of angular movement to the arms connected thereto and thus rotates the different reflectors to different degrees of 30 opening.

In operation, the keys of the piano are employed in the usual way for vibrating the 35 strings by percussion. The sound wave reflectors are normally open and the damped compressional waves produced within the casing are emitted therefrom. The metal lining 50 serves to form resonating chambers within the piano casing, one chamber being 40 over the sounding board, and the other underneath.

When it is desired to modulate the sound emitted the foot pedal 36 is depressed, thereby elevating the rod 35 and rotating the bell crank lever 32 in a counter clockwise 45 direction against the pressure of the spring 40. This causes the link 31 to be moved towards the right of Figure 2 thus rotating the arm 30, the shaft 25 and the radial arms thereon in a counter clockwise 50 direction as seen in Figure 3. The links 24, 28 are thus moved to the right, together with the connecting rod 23 and the upper connecting rods 22.

The lower group of sound wave reflectors 55 having arms 21 of substantially the same length, are closed at a uniform rate, but the upper group having arms of different lengths are closed at various rates. Thus the reflector at the extreme left of Figure 60 1, i. e., adjacent the bass strings of the piano, are closed at the slowest rate, while the reflector at the extreme right, i. e., adjacent the treble strings, are closed at the fastest rate. The intermediate reflectors close at 65 rates intermediate these extremes. The an-

gular positions of the arms 21 of the upper reflectors are such that when the pedal 36 is fully depressed, all of the reflectors are fully closed. Upon releasing the pedal, the reflectors are restored to normal by the action of the spring 40.

Thus it will be seen that there is provided a musical instrument in which the musical tones of high pitch, which are produced by strings of relatively small mass, with proportionally small energy, are differently controlled from notes of low pitch and having greater energy. The arrangement illustrated is intended to restrict the emission of the stronger tones to a greater degree 70 than in the case of the weaker tones. A more even depth of tone can thereby be produced.

The invention upon which this application is based is broader than the specific embodiment shown and described for the purpose of illustrating at least one of the ways in which it may be employed. The scope of the invention is therefore to be understood as not being limited by the present specific description. I intend no limitations other than those imposed by the claims.

What is claimed is:

1. In a musical instrument of the percussive type, the combination with tuned strings, of a casing having oppositely disposed apertures, controllable closures for said apertures arranged in groups, and means for actuating the closures of at least one of said apertures at a speed relatively different from the speeds of the others of the 95 closures.

2. In a musical instrument of the percussive type, the combination with tuned strings, of a casing having an aperture for 100 the emission of sound, and a plurality of controllable closures for said apertures, each of said closures being arranged to be operated at relatively different speed.

3. In a musical instrument of the percussive type, the combination with vibratory elements of relatively different mass, of a 110 casing having an aperture for the emission of sound produced by said elements, a plurality of closures positioned in said aperture, and means for simultaneously actuating said closures by different amounts whereby different sound emitting spaces are obtained.

4. In a musical instrument of the percussive type, a plurality of hammers, strings arranged to be set into vibration by the impact thereon of said hammers, a plurality of keys for actuating said hammers respectively, a casing for the instruments, said casing having an aperture for the emission of sound therefrom, a plurality of movable sound wave reflectors positioned in said aperture, each comprising a centrally pivoted member, an arm of predetermined length mounted on each member, the arms 120 125 130

of the different reflectors being relatively different in length, and operating means joining the outer ends of said arms for rotating said reflectors at relatively different 5 rates of speed.

5. A sound wave control system comprising a plurality of centrally pivoted sound wave reflectors, each having an operating arm extending outwardly therefrom at an 10 angle, the arms of said reflectors being relatively different in length respectively and extending at relatively different angles, and

operating means for said reflectors comprising rods interconnecting the outer ends of said arms arranged so that in one position 15 said reflectors effectively suppress sound waves, and upon predetermined actuation of said operating means said reflectors are rotated to relatively different angular positions.

Signed at Rome, in the Province of Rome and Kingdom of Italy this second day of March A. D. 1927.

JOHN HAYS HAMMOND, JR.
